BLINKING LIGHT SYSTEM

George C. Davis, Lansing, Mich., assignor of one-third to Percy N. Orton and one-third to Peter G. Scoles, Lansing, Mich.

Application April 11, 1935, Serial No. 15,922

1 Claim. (Cl. 177—337)

This invention relates to so-called blinking or flashing light systems, and is intended especially for use in connection or association with the ignition systems of automobiles, although it may be employed with equal advantage in the operation of any arrangement of signal lights which are desired to be of a particularly noticeable character.

The object of this invention consists in the special construction and coordination of electrical generation means together with selected induction, conductors and current distributing switches substantially as hereinafter described.

While it is preferred to include neon tube lights in the operation of this invention, it is not intended to limit the system to any certain nature or design of the lights, or to the precise situations thereof upon the automobile, as those features may be obviously modified.

The drawing represents diagrammatically a top view of an automobile with the lighting and ignition systems constructed in accordance with this invention applied thereto.

Considering the drawing, an automobile 1 is provided with dust guards 2, 3, 4 and 5 over the wheels, and upon the guards are placed signal lights 6, 7, 8 and 9 of any chosen structure and character.

A battery 10, or other source of electric current, is included as shown, usually with one pole grounded as at 11. Connected with the battery is a suitable ignition system switch 12, a conductor 13 leading therefrom to the battery. The switch is connected by conductor 14 with the low tension coil 15 of an inductorium 16, with which is connected the customary condenser 17 that may be grounded as at 18. The circuit in the coil is repeatedly interrupted by the make and break devices 19, which may be of any chosen construction. The device is operated by the eccentric 20 rotated by the motor of the automobile. It is held to be within the purview of this invention to substitute any desired form of electro-magnetic make and break devices. The devices 19 are grounded at 21.

The induction means may have more than one high tension coil. In the drawing the high tension coil 22 is grounded as at 23 and is connected by way of conductor 24 with a distributor 25, one contact of which 26 is shown as connected by the conductor 27 with one of the sparkplugs 28 of the motor in the engine frame and having, therefore, a ground as at 29.

The second high tension coil 30, by way of conductor 31 is grounded as at 32. The other end

of the coil by way of the conductor 33 is connected with a switch arm 34. It will be noted that the switch arm 34 may sweep several contacts, 35, 36, 37, 38, 39 and 40. The last numbered contact is connected with conductor 34 of the ignition system. It is believed to be apparent from the drawing, if the switch arm 34 is moved to the left an interrupted current will be directed by way of conductor 42 through the left front signal light 6 to ground 43. If the arm bridges contacts 35 and 36, both lights 6 and 8 on the left hand side of the machine will blink. If the arm is still further moved to the left, bridging contacts 36 and 37, both rear lights 8 and 9 will flash repeatedly and have the effect of a stopping signal. If the arm 34 is moved onto the contact 38 at the right, the high tension induced current passes by conductor 46 to the right hand front light 7 and to ground 47. If the arm bridges contacts 38 and 39, both front and rear right hand lights wink repeatedly, current reaching the rear right hand light by way of conductor 48, and through the light to ground 49.

It will be noted that when the switch arm is applied to contact 36, the current passes by way of conductor 44 to the left hand rear light 8 and thence to ground 45. It will be observed also that the high tension coil 30 which serves the lights is provided with a separate interrupter 50 as shown in the drawing. The make and break device 50 may be introduced at any convenient point. As in the case of the interrupter 19, the device 50 is rotated by the motor, but at a different rate, for the following reasons: The second interrupter is used to obtain a longer interruption of the current causing a greater delay between the blinks of the lights. If the lights are connected with the sparkplugs directly, the alternating current changes are so rapid as to result in making the lights glow almost steadily. Whereas, the object of this invention is to produce a distinct and noticeable blinking of the lights, and that is the function of the second interrupter.

In the operation of this invention, as stated in the above explanation, either left or right front lights may be caused to flash independently, or left hand front and rear lights may be made to blink at the same time, and the same is true of the right hand front and rear lights. Also, the rear lights may be served current and wink together as stopping lights. It will be likewise understood, that when the switch arm 34 is moved onto contact 40, the current by way of conductor 55

41 is directed to the distributor and sparkplugs. This arrangement of switch arm 34 is ordinarily unnecessary, and is reserved as an emergency operation in the event of trouble in the ignition 5 circuit.

Having now described this invention, and the manner of its use, I claim:—

In a blinking light system, the combination with a source of electric current, of means for 10 generating induced current comprising a low tension coil and conductors connected with the said source, an interrupter arranged to make and break the low tension current, said induction

means having two high tension coils arranged to be inductively acted upon by the low tension coil, a system of signal lights connected with one of said high tension coils, a second interrupter in circuit with the said lights coil and 5 adapted to cause the lights to blink, electrical switching means and conducting connections constructed and arranged to control the application of current to said lights, and a sparkplug ignition system connected with the second of 10 said high tension coils.

GEORGE C. DAVIS.
